(57) **CLAIM**

The ornamental design for a hair dryer, as shown and described.

DESCRIPTION

FIG. 1 is a front elevational of a hair dryer showing my new design;

FIG. 2 is a rear elevational view thereof;

FIG. 3 is a left side elevational view thereof; the right side elevational view thereof being a mirror image of the left side elevational view shown

FIG. 4 is a top plan view thereof;

FIG. 5 is a bottom plan view thereof; and,

FIG. 6 is a left side perspective view thereof.

The electrical cord and plug have been omitted from FIGS. 5 and 6 for ease of illustration. The electrical cord is shown broken away in FIGS. 1, 2, and 3 to indicate indeterminate length. The electrical cord is shown in an alternate position in FIG. 3.
